UNITED STATES PATENT OFFICE.

WALTER F. LUFF AND ALFRED WM. TURNER, OF HANDSWORTH, BIRMINGHAM,
ENGLAND.

AIRCRAFT.

1,278,179.

Specification of Letters Patent. Patented Sept. 10, 1918.

Application filed February 13, 1917. Serial No. 148,446.

To all whom it may concern:

Be it known that we, WALTER FISHER LUFF and ALFRED WILLIAM TURNER, subjects of the King of Great Britain and Ireland, residing at 37 Murdock road, Handsworth, Birmingham, in the county of Warwick, England, have invented certain new and useful Improvements in Aircraft, of which the following is a specification, reference being had therein to the accompanying drawings.

This invention relates to aeroplanes suitable for use to carry one, two, several or many passengers or to carry merchandise, likewise suitable for use to carry artillery guns and ammunition for use in such guns, likewise to carry missiles to be dropped from sky locations.

This invention has for its object the construction of an aeroplane of great floating stability, for use for peaceful pleasure, or mercantile purposes; also for use as "a dreadnought artillery-carrying aeroplane".

It has been previously proposed in the construction of flying machines of the heavier-than-air type, to use a centrally situated elliptical body or shell with lateral supporting members, one on each side, such supporting members being rotatably mounted upon two shafts respectively extending transversely of the said elliptical body. It has also been previously proposed to use horizontally and vertically mounted propellers in the construction of aeroplanes, and it has likewise been previously proposed to use collapsible propellers, in some cases having four helical blades, all of which would be pivoted to collapse around a common center, in other cases with two blades hinged to collapse near a common center but to in addition also expand upward to the horizontal position or extend beyond the horizontal position into a partly collapsed position above the horizontal.

We will now proceed to describe with reference to the accompanying drawings, the manner in which our invention is constructed and used.

Figure 1 represents a front view of our improved aircraft structure.

Fig. 2 represents a back view of the aircraft structure shown at Fig. 1.

Fig. 3 represents an elevation of the collapsible propeller in the opened position.

Fig. 4 represents a plan of Fig. 3.

Fig. 5 represents an elevation of the collapsible propeller in the closed position.

Fig. 6 represents a plan of Fig. 5.

In carrying out the construction of our invention, we provide a central-house *a* as a central structure to contain a smaller house, termed the engine-room *b*, within which are provided the engine, petrol supply storage vessel or vessels, also electric accumulators and all other requisites, providing also ample room for the pilot to be located and work. Outside the engine-room *b*, near each end of the central-house *a* are situated shell-guns or shot-guns at locations *c*, one at each end, these guns being protected by suitable armor-plating, not shown.

From each side of the central-house *a* extend lower spars *d* the end of each spar *d* supporting and carrying a box-shaped plane or plane-house *e*, one box-shaped plane or wing at each side of the central-house *a*.

At either end of each plane-house *e* is provided an engine *f* that drives a propeller *g*, each plane-house *e* being thus provided with an engine *f* and a driven propeller *g*.

We provide suitable rudders *h*, but the usual tail-piece is dispensed with entirely.

On each side of the engine-room *b* situated within the central-house *a* is provided a quick-firing gun which is located at *i*.

The crew would usually include a separate gunner for each of the guns carried on our aircraft structure, and the pilot from within the engine-room *b* would control all the propellers, by means of electric-current conducting-wires *j* carried on the upper spar *d*, and through such conducting-wires *j* the required electric sparking is made within the several engines (such engines are not shown) to so start and continue the necessary alternate explosions within each cylinder of each petrol-engine or other explosive-vapor engine, such engines not being shown because they are not new in themselves.

The electric-current to any one or more engines situated on our improved aeroplane, or aircraft-structure can be cut off by the pilot to so stop one, two, three, or all of the engines, as may be required.

At one end of the central-house we provide a large propeller *k* driven from an engine situated within the central-house engine-room *b*.

In some cases we use two additional en-

gines and medium sized propellers *l*, at the same end of the machine as that where the larger central-house propeller *k* is situated, but such additional engines and their propellers would be situated between the central-house *a* and the two plane-houses *e*, one on each side of the central-house *a*, the spars *d* being extended in width into a suitable conformation and area, to safely carry 10 the engines and their propellers.

We in some cases provide one, two, or more horizontally situated propellers *m*, such propellers being carried on shafts such as *n* that extend from the engine-room *b* upward vertically within the central-house *a*, then pass through the roof-ridge of central-house *a* and thence upward outside the roof-ridge a suitable distance, as shown at Figs. 1 and 2. These horizontally situated propellers may in some cases be non-collapsible, as shown in use in Figs. 1 and 2, but in other cases we construct the propellers with a closing arrangement having a central sliding boss and hinged top parts, to so permit 25 of the horizontally situated propellers expanding out into the required horizontal position for use in rising vertically and quickly, or of closing somewhat like a closed umbrella.

30 Figs. 3 to 6 inclusive illustrate the several parts of our collapsible propeller, where a five-bladed propeller is shown having each of its blades *p* hinged to the upper-end of a connecting-rod *q*, at *r*, the lower ends of such 35 connecting-rod *q* being hinged to the central sliding-boss at *s*. The inner or root-end of each blade of our collapsible propeller is hinged to an upper central disk *t*, from which extend snugs *u* that are provided to 40 prevent the blades expanding upward beyond the true horizontal position suitable for driving purposes. We have not shown the twist or curve of each blade, but simply 45 shown their position when expanded into the driving usable position, likewise their position when collapsed and out of use.

To the upper central disk *t*, we solder or otherwise secure or attach the hollow cone *v*, the apex *w* of which will offer the minimum of resistance to atmosphere when the 50 machine is rising.

The external chamber *o* of the roof of the central-house *a* of our improved aeroplane or aircraft-structure, also of the roofs of our 55 two plane-houses or wing-houses *e*, is so constructed as to present an external convex configuration with a corresponding under, internal concave roof configuration which is provided as a recess or pocket (in each case) 60 that always retains a cushion of air, that supports all three houses, *a* and *e* to a certain extent, irrespective of the continuous rush of air through each of the houses *a* and *e* under the cushioned air, while the machine is traveling.

In using our improved aeroplane, we start the engines *f* that drive the propellers *g*, or start the engine situated within the engine-room *b* to drive the propeller *k*; at the same time we start one of the engines located within the central-house engine-room *b* to thereby revolve the two or more horizontally situated propellers *m* thereby causing the structure to rise; the course of the traveling aeroplane then being governed by the pilot using 70 the rudders *h* and the house-shaped or box-shaped wings or elevating-planes *e*. 75

When the pilot wishes to descend, he would slacken the pace of the various engines, thus reducing the speed of the main 80 revolving propellers *g*, likewise of the horizontally situated propellers *m* and when using our horizontal collapsing propellers, would by the slowing down of the speed cause the blades *p* to collapse from the expanded position shown at Fig. 3, into the collapsed closed position shown at Fig. 5. One great advantage to be gained by adopting 85 and using our horizontal propellers on our improved aeroplanes, is that in rising 90 from a small field or other fenced-in location bounded by a closely situated hedge, fence, or wall, our machine can rise vertically without any preliminary long run on the ground.

95 The description hereinbefore set forth relates to the use of our central housed and wing-housed aeroplane as a dreadnaught war machine. When we wish to use our invention for peaceful services, we simply dispense with the guns and their munitions and then use our large structures as omnibus-aeroplanes. Nevertheless we can construct small sized machines under this our invention on same lines, for use of one, or two 100 persons per voyage.

Having now particularly described and ascertained the nature of our said invention, and in what manner the same is to be performed, we declare that what we claim is:— 110

1. In an aeroplane the combination with a central house, a propeller mounted in front of said central house, horizontally extending propellers arranged above said house, spars extending laterally from the opposite sides of said house, box-shaped planes carried by the outer ends of said spars, a propeller mounted upon the rear end of each of said box-shaped planes, a motor arranged within each of said box-shaped planes for driving said propellers, a vertically extending rudder arranged in front of each of said box-shaped planes, and the motors arranged within the box-shaped planes and said central house adapted to be controlled from said central house substantially as and for the purpose specified. 115 120 125

2. In an aeroplane the combination with a central house, said central house having an inclined roof, said inclined roof having a 130

convex configuration, horizontally extending propellers arranged above said inclined roof, a large propeller arranged in front of said central house, box-shaped planes arranged 5 at each side of said house and lying in the same plane, a small propeller arranged at the rear of each of said box-shaped planes, a vertical rudder arranged in front of each of said box-shaped planes, and the tops of 10 said box-shaped planes being of a convex

configuration substantially as and for the purpose specified.

In testimony whereof we affix our signatures in the presence of two witnesses.

WALTER F. LUFF.
ALFRED WM. TURNER.
